UNITED STATES PATENT OFFICE.

EUGÈNE LOUIS DOYEN, OF PARIS, FRANCE.

FORCEPS.

SPECIFICATION forming part of Letters Patent No. 614,708, dated November 22, 1898.

Application filed January 31, 1898. Serial No. 668,635. (No model.)

To all whom it may concern:

Be it known that I, EUGÈNE LOUIS DOYEN, surgeon, a citizen of France, residing at Paris, France, have invented certain new and useful Improvements in Forceps or Like Instruments, of which the following is a specification.

My invention relates to forceps or pincers for use in surgical operations; and it consists in auxiliary pressure-increasing devices attached to the lever-arms or handles to increase their nipping or compressing powers.

The nature of the improvement will be best understood by reference to the accompanying drawings, in which—

Figure 1 shows a pair of forceps provided with the auxiliary pressure-augmenting device in operative position. Fig. 2 is a fragmental bottom view along the line X Y of Fig. 1.

A and B are the lever-arms or handles, pivoted at 7 and terminating in the nipper-jaws A' and B'. About midway between the thumb or finger eye and the pivot-point 7 on the handle A is a slot in which a pawl c is pivoted at 1 and capable of a limited swing. A spring 6, secured to the outer edge of the handle A, presses against the rear end of the pawl C and tends to deflect its outer toothed end downwardly. The handle B does not terminate in the usual thumb or finger eye, but has an enlargement F, which is slotted to receive the enlarged rounded end of the auxiliary lever-arm D, which is pivoted therein. This rounded end is cammed or provided with a tooth 8, with which the spring-pressed pawl c, which is adapted to enter the slot in the arm B, engages. The lever-arm D is provided with a thumb or finger eye to correspond with the one in the handle A. It is also provided with a pin 4, which engages with a swinging hook or catch 3 on the end of the handle B, by means of which the lever-arm D may be held in place against the handle B. The end of the pawl C projects sufficiently through the slot in the handle B to permit of its being lifted against the pressure of the spring 6 out of engagement with the tooth or cam 8 on the lever-arm D.

At the lower end of the handle A is pivoted a swinging rack-bar 5, having teeth inwardly disposed and adapted to engage with a pro-

jection or lug E upon the lower end of the handle B. A shoulder 9 prevents the rack-bar when swung up from passing the lug E. 55

The operation of the device is as follows: If only a normal pressure is required, the forceps may be used like ordinary surgeons' pincers by securing the auxiliary-lever arm D, when out of engagement with the pawl C, 60 down against the handle B by the pin 4 and hook or catch 3. When the parts are disposed in this manner, the forceps may be applied in the usual way, or, if desired, the rack-bar 5 may be swung up into engagement 65 with the lug E, by which means the handles may be locked at any desired pressure against opening or releasing the nipper-jaws; but when it is desired to increase the pressure thus obtained the lever-arm D is opened out 70 into engagement with the pawl C, and as D is forced back toward its former or closed position against the handles B the pressure exerted by the nipper-jaws is largely increased through the medium of this additional lever- 75 age. As the handles A and B are brought closer together by this means, the lug E advances in engagement along the rack-bar 5, which has sufficient spring to allow such a movement, and thereby removes all strain 80 from the pawl C and lever-arm D.

In order that the forceps may be readily and frequently cleaned, I have provided tapering pivots at 1, 2, and 7 of such a construction as to be easily removable, so that 85 the parts may be detached and assembled without difficulty. All the other attachments have been secured by screws with the above object in view.

Although my invention applies to forceps 90 or pincers for use in surgical operations, it is obvious that it may be applied in metal-working and various other branches, so I do not desire to limit myself to any specific branch.

What I claim is—

1. In forceps or like instruments the combination of the two pivoted handles, with a pawl pivoted on one of said handles, and an auxiliary lever pivoted on the other of said handles and adapted to engage with said pawl, for the purpose specified. 95

2. In forceps or like instruments the combination of the two pivoted handles, with a spring-pressed pawl pivoted in a slot in one

of said handles, and an auxiliary lever, having an enlarged toothed end, pivoted in a slot in the other of said handles and adapted to engage with said pawl, for the purpose specified.

3. In forceps or like instruments the combination of two pivoted handles with a lug or projection secured on one of said handles, a swinging rack-bar pivoted on the other of said handles and adapted to swing into engagement with said lug or projection, and pressure-increasing devices secured upon each of said handles operating substantially as and for the purpose specified.

4. In forceps or like instruments, two pivoted handles A and B, terminating in nipper-jaws, a spring-pressed pawl pivoted in a

slot in the handle A, an auxiliary toothed lever pivoted in a slot in the handle B and adapted to engage with said pawl, means 20 for securing said auxiliary lever against the handle B, a shoulder and lug or projection secured on one of said handles, and a rack-bar pivoted on the other of said handles and adapted to swing against said shoulder into 25 engagement with said lug or projection, substantially as and for the purpose described.

In testimony whereof I have hereunto set my hand in presence of two subscribing witnesses.

EUGÈNE LOUIS DOYEN.
